UNITED STATES PATENT OFFICE.

EDWARD E. CLEMENT, OF WASHINGTON, DISTRICT OF COLUMBIA, ASSIGNEE, BY
MESNE ASSIGNMENTS, TO FREDERICK C. STEVENS, OF ATTICA, NEW YORK.

TELEPHONE-EXCHANGE SYSTEM.

1,107,145.

Specification of Letters Patent. Patented Aug. 11, 1914.

Application filed June 22, 1906. Serial No. 322,860.

To all whom it may concern:

Be it known that I, EDWARD E. CLEMENT, a citizen of the United States, residing at Washington, in the District of Columbia, 5 have invented certain new and useful Improvements in Telephone-Exchange Systems, of which the following is a specification, reference being had therein to the accompanying drawing.

10 My invention relates to telephone exchange systems and has for its principal object the improvement of such systems by decreasing the number of operators required for a given number of lines and facilitating 15 their work to the highest possible degree.

In order to attain my object I employ a combination of apparatus and circuits, portions of which are of the well known manual type and other portions automatic in 20 their operation, such combinations being known as "semi-automatic".

A very important corollary or subsidiary object of the invention is to increase the capacity of existing exchange switch-boards 25 of the manual type and to render it possible to convert them into semi-automatic equipments, at the same time increasing their efficiency as well as their capacity.

Other objects will appear from the description hereinafter.

Briefly stated, my invention comprises a system in which the subscribers' lines terminate on the usual answering jacks in a manual switchboard, but instead of being 35 provided with multiple jacks for connecting purposes, the lines are provided with multiple terminals in automatic switches of any desired or suitable type. The operator is provided with cord circuits of a single-plug 40 type and terminating before the operator in an answering plug. The usual supervisory lamp and relay for this plug are provided as well as a controlling relay, a cut-off and line relay for each line, and an operator's listening key. From the answering plug of each cord a pair of trunk conductors extend directly to an automatic selector switch containing multiple terminals through 45 which the subscribers' lines may be called. Associated with the cord is a group of keys 50 by which the operator may direct groups of impulses over the trunk to control the movements of the automatic switch or switches, and finally, automatic apparatus associated

with the switching device tests the wanted 55 lines and sends out ringing current in case the line is found clear.

This system is applied to existing manual plants by severing the ordinary cord circuits and using them as I have described, each end 60 of the ordinary cord circuit furnishing one complete terminal for an automatic trunk. The subscribers' lines are then disconnected from the multiple jacks, preferably at the intermediate distributing frame, so that the 65 multiple jack strips and their cable may be removed bodily. Experience demonstrates that an operator when relieved, as in this case, of the burdens of testing, ringing and supervising, can do more than twice the 70 work and can handle more than twice as many lines as under the old system. Thus, each operator can handle two positions, so that only half the number of operators are needed to manage the same switchboard, 75 but where the capacity of the board is to be increased, answering jacks and lamps are added in the panels left vacant by the removal of the multiple jacks. The number of 80 automatic switches required, and the amount of cable and subsidiary apparatus, is relatively small in cost when the increased capacity and the great efficiency of the service are taken into account.

My invention is illustrated as to one embodiment in the accompanying drawings in which—

Figure 1 is a diagram of a subscriber's line and a central office switchboard circuit in which it terminates, together with an answering plug and a portion of the cord circuit thereof. Fig. 2 is a similar diagram complementary to Fig. 1 showing a trunk extending from the cord circuit to an automatic switch. Fig. 3 is a diagram of the 95 operator's controlling circuits and keys.

The system of my invention is herein illustrated and described as applied to an exchange of but one hundred lines, but it is to be understood that the number of lines 100 is limited only by the selecting apparatus of Figs. 2 and 3, the selective apparatus of Fig. 2 being of any desired type. Many types of impulse-controlled selective and connective apparatus are now known to the 105 art, some of them providing for indefinitely large exchanges by a system of successive selective devices, the subscriber's lines being

found only in the last connector of the series of switches. With devices of Fig. 2 adapted to respond to impulse control, in a manner well known to the art, the devices of Fig. 3 require a similar extension in that the sets of keys must be increased to provide for the sending of as many sets of impulses as the devices of Fig. 2 require, but the extension of the apparatus of Fig. 3 is simply the duplication of the sets of keys already shown in that figure.

Referring first to Fig. 1, A is a subscriber's station equipped with the usual talking and signaling apparatus such as may be found in every modern common battery exchange system. This comprises a transmitter, receiver, switch-hook, ringer and condenser, with or without an induction coil according to the make of the instruments used. In the diagram no induction coil is shown, however. The line wires are marked 1-2 and extend to the central office C where they terminate upon the contacts of the cut-off relay N. These contacts are shown as armatures, but commercially they are usually contact springs controlled by the armature of the relay. They are normally electrically as shown, connecting the wire 1 to ground on one side, and wire 2 to line relay M and thence by wire 5 to the battery B on the other. When the subscriber removes his telephone from the hook, current will flow through the line relay, energizing it and lighting the lamp m by closing the branch circuit 6 to ground. Passing from front contacts of the cut-off relay are two extension wires 7 and 8 terminating at the answering jack J and having parallel connections 9 and 10 to the multiples or connecting terminals s^2 , which are in the banks of several automatic switches, presently to be described.

Coöperating with the answering jack J is an answering plug P having tip and sleeve contacts through which the cord conductors 11 and 12 pass as far as the condensers c, and being inductively connected therethrough to the trunk conductors 13 and 14 leading to the automatic switch S of Fig. 2. Connected between the battery and the sleeve side 11 of the cord circuit is the relay R which controls the battery supply to the armature contacts of the supervisory relay R', while passing through its own coils is the supply of current both for the subscriber's station in talking, and for the cut-off relay N which is usually made with 500 ohms resistance in its windings, composed of many turns of fine wire connected in a ground tap through the sleeve wire 7 of the line extension. The supervisory relay R' on the other hand is tapped off to ground from the tip side 12 of the cord circuit, and directly controls the supervisory lamp r associated with the plug P.

The trunk wires 13-14 extend to a selector or connector switch or switches, of which that shown in Fig. 2 is given as an example. As to their mechanical parts, the switches are of the type shown in patents 70 to Keith and Erickson, 815,176 and 815,321, both dated March 13, 1906; with the exception that I prefer not to employ a so-called "side switch" shown in those patents, using combinations of relays by preference for 75 purposes of control. The main mechanical features, however, are the same, hence I have not thought it necessary to describe this type of switch herein except diagrammatically. The banks of contacts s^2 are in 80 curved rows, each switch containing one or more of these rows as shown in the said patents, and having a spindle s carrying wipers s' which are adapted to be brought into connection with any pair of contacts 85 in any row by a double motion of the spindle, one component of the motion being vertical produced by a ratchet controlled by the magnet s³, and the other component being rotary produced through a circular 90 ratchet by the so-called rotary magnet s⁴.

The trunk 13-14 shown in the diagram, leads to the connector switch S, shown in Fig. 2, and this switch is operated by means of impulses over the two sides of the trunk, 95 in a manner which is generally familiar to those acquainted with the art. In order to do this I provide the operators with impulse transmitters or "senders." For convenience I will first describe this arrangement as it is shown in Fig. 3, and will then proceed to point out its effect upon the apparatus of Fig. 2. In Fig. 3, Q⁰, Q, Q', Q², Q³, Q⁴, Q⁵, etc., are a set of wheels mounted on and turning with a common 100 shaft, which may be driven in any suitable manner. The wheel Q⁰, puts battery and ground alternately on the wire 29, which for purposes of illustration represents the metallic shaft connection between the wheels. The wheel Q which is insulated from the shaft is grounded, has an insulating spot in its periphery, and controls by means of this spot the locking and unlocking wires 30 and 31, in a manner which will appear from the statement of operation. The wheels Q', Q², Q³, Q⁴, Q⁵, etc., are number wheels, the first one having one tooth, the second two teeth and so on up to ten teeth. (For simplicity of illustration only five wheels are shown). Around these wheels are three sets of pens, connected to the three sets of keys K', K², K³. As the wheels revolve from the normal position of rest in which they are shown in the figure, they first make connection with the upper pens, q', then with the pens q², then with those, q³. The first set with their buttons or keys, K', transmit the tens digit of any number, the next set transmit the units digit, and the third set transmit 110 115 120 125 130

the ringing number for party-line work. All this will appear more clearly from the statement of operation.

The keys, K' , K^2 , K^3 are of the so-called self-latching selective ringing type now in common use on manual switchboards, and employ the principle shown in the patent to Ham, No. 605,097 granted June 7, 1898. When any key is pressed down it pushes back the latch and releases the one that was previously down, then latching itself. The keys of each row are thus interlocking, the rows being independent; thus one key of each row remains depressed. Each set of keys has a common wire, this for the sets K' , K^2 , being marked 32, these two being joined together and carried to a back contact of the relay R^4 , while that for the set K^3 is marked 33 and carried to another back contact of the same relay, separately controlled. The numbers to be sent are set up, by depressing the keys, and then the signal is started at the beginning of a rotation of the shaft, when the first tooth of each wheel is about to strike its pen q' , by the relay, R^4 , being deenergized, while the relay R^5 remains energized. The trick of this is in the arrangement of the spring pens q^5 , q^6 , on the wheel Q . This wheel is rotated with the others in the direction of the arrow, and its insulating spot passes first under the spring pen q^5 , momentarily cutting ground off of that and the wire 31, then under the pen q^6 , taking ground off of that. In calling the number wanted, which we will assume to be 32-3, the operator plugs into the calling jack, then presses down button No. 3 of the set K' ; No. 2 of the set, K^2 , and No. 3 of the set K^3 . The buttons of the sets K' and K^2 have their several individual wires connected to the springs on the several individual wheels Q' , Q^2 , etc., and the effect of pressing down the buttons as mentioned is to connect the pen q' of the wheel Q^2 through the springs k' of the button k to the wire 32. At the same time the pen q^2 of the wheel Q^2 is connected through the springs k^2 of the button k^2 to the wire 33 and the spring q^3 of the wheel Q^3 is connected through the springs k^3 of the button k^3 to the wire 32. The set of buttons, K^3 , also have what I may call starting springs k^3 . Keys of the type shown in Ham, cited, pass downward through a maximum travel and return slightly to engage the locking shoulder. I take advantage of this and so adjust the springs k^3 that they close at the maximum travel and break upon the slight return, being open when the key is in its final locking position. The springs k^3 , however, remain closed when the key is locked. This set of buttons being the last, or ringing set, the number is ready for transmission when any one of them is depressed, hence any one of these buttons not

only finishes setting up the number, but by closing the springs, k^3 , puts ground on the starting wires 37 and 38, which pass to the two relays, R^4 , R^5 , respectively, and thence through the common return wire 39 to battery B and ground. Both the relays pull up, and both lock, the locking circuit of the relay R^4 being as follows: B, 39, R^4 , r^5 , 30, q^6 , Q and ground. The locking circuit of R^5 is as follows: B, 39, R^5 , r^7 , 31, q^5 , Q and ground.

Having thus set up the signal and put it in condition to be started at the beginning of a revolution of the main shaft, the operator's work is finished. She pays no further attention to the connection until the subscribers have completed their conversation and have hung up, whereupon the relay R' in Fig. 1 lets go, and the lamp, r , lights to call for disconnection. The operator then pulls the plug P .

The signal having been set up as described, the apparatus of Fig. 3 then operates as follows: The wheel, Q , in revolving will bring the insulating spot under the pen, q^5 , at first, and might thereby cut off the relay, R^5 , prematurely, but this is provided for by making a branch locking circuit 310 which is controlled through a contact of the armature r^6 and a ground wire 36 of the starting relay R^4 . Hence, as long as the relay R^4 is energized, the relay R^5 cannot be affected. Moreover, it will be observed that the wires 32 and 33 remain disconnected from the wires 15-16 until the relay R^5 is energized, while the relay R^4 is deenergized. This condition is brought about when the insulating spot reaches the pen q^6 . The relay R^4 then lets go, and we have a continuous circuit from wire 32 as follows: 32, r' , 34, r^3 , 16, and to trunk wire 14. We also have a circuit for wire 33 as follows: 33, r^2 , 35, r^4 , 15, and the other trunk wire 13. The insulating spot reaches the pen q^6 just before the first tooth on each wheel reaches its pen q' ; hence as soon as the above desired condition is attained, the set of battery impulses which has been determined by the key k of the set K' , comes over the wire 32 to the wire 16 and so onto the wire 14 of the trunk, through which it passes into Fig. 2 to the relay R^6 which will be presently described, and which I shall call for convenience the vertical relay. At the end of this group of impulses, the teeth on the wheels will have gotten around to the pens q^2 and so the next group of ground impulses determined by the key k^2 will pass onto the wire 33 and so to the wire 15 and the trunk wire 13, through which they reach the relay R' in Fig. 2 which will also be presently described and which I shall for convenience call the rotary relay. The names of these two relays are quite accurate in this system, because the relay R^6 does

really produce a vertical motion of the switch S , while the relay R^7 produces a rotary motion thereof. At the end of this second group of impulses, the teeth on the 5 wheels have gotten around to the third set of pens q^3 and the battery impulses determined by the keys k^5 then come through the wire 32 onto the wire 16 and so again to the trunk wire 14 and to the vertical relay 10 R^6 . After this, the insulating spot on the wheel Q reaches the spring q^5 and momentarily cuts off the ground therefrom. Since the relay R^4 is already deenergized, this 15 breaks the locking circuit of the relay R^5 15 and it lets go, disconnecting the wires 15—16 from the wires 35—34, and leaving the apparatus free for another operation.

Referring now to Fig. 2, I will briefly describe the switch operation. The switch 20 spindle controls a pair of springs s^5 which it opens when it is down in its normal position of disuse, for restoring purposes, as will presently appear. s^6 is the release magnet of the switch, which when energized 25 moves the detent pawls from the respective ratchets of the spindle, s , allowing the spindle to drop down and rotate back to zero, as fully described in the patents referred to. This release magnet is under 30 the control of the relay R^{10} which in turn is controlled by the relays R^6 and R^7 . It is also under the control of the test relay R^{11} . R^{12} is a ringing-selection control relay, R^{13} is a trunk cut-off relay and R^{14} is a ringing 35 relay controlled by the commutator X which is common to the entire exchange. R^{15} is a slow acting relay, preferably a solenoid, which connects the test relay R^{11} , as controlled by the first ringing impulse, 40 and at the same time opens the generator circuit 40—41, while the proper current is being selected. R^{10} to R^{21} , inclusive, are selective relays for enabling one or the other of the ringing generators, G , G' , G^2 and 45 G^3 , to be connected onto the ringing contacts of the ringing relay, R^{14} , the particular generator being determined by the number of impulses received through the relay R^{12} which operates the relays R^{16} , R^{19} , R^{17} , 50 R^{20} , R^{18} , R^{21} , in succession, each of them locking as it operates.

The operation of this trunk scheme is as follows: In selecting the number we have assumed 32—3; we have first three impulses 55 over the wire 14 to the relay R^6 , then two ground impulses over the wire 13 to the relay R^7 , and then three impulses again over the wire 14 to the relay R^6 . The first three impulses coming over the wire 14 60 caused the relay R^6 to pull up three times, each time closing the following circuit: B, 42, 43, 44, s^3 , 45, 46, 47, and ground to battery. The vertical magnet s^3 steps the spindle s of the switch up three steps, so that 65 the wipers s' stand opposite the third row

of contacts. Two impulses then come over wire 13, affecting the relay R^7 which pulls up twice, the first time closing the following circuit: B, 42, 48, R^9 , 49, 50, armature of R^{10} , 51 to ground and to battery. The 70 relay R^9 instantly pulls up, cutting off the vertical magnet, s^3 , and locking itself by the following path: B, 42, 48, R^9 , r^9 , 52, 50, 51 and ground back to battery. The vertical magnet s^3 is therefore cut off for the 75 rest of the transmission. The rotary magnet s^4 , however, gets current each time the relay, R^7 , is energized, over the following path: B, 42, 43, 44, s^4 , 53, 54, 55 and ground back to battery. The rotary magnet s^4 turns 80 the spindle s two steps, so that the wipers s' rest on the second pair of contacts in the third row, or No. 32. Three impulses now come over the wire 14, causing the relay R^6 again to pull up three times. Each time 85 it closes the following local circuit: B, 42, 56, R^{12} , 57, 46, 47, and ground back to battery. As a branch of this same circuit, the wire 58 comes in from battery wire 42 and goes to 57, 46, 47 and ground, so that the 90 solenoid R^{15} is energized as well as the relay R^{12} . At this point in the development of the connection immediately following the closure of the contacts of relay R^6 at 95 the beginning of the first generator-selection impulse, two things occur simultaneously:

(1.) The solenoid R^{15} attracts its core, opening the wires 40—41 and closing the switch 62 whereby a test circuit is formed through elements B, 42, 62, R^{11} , 63, to upper s' , which at this moment is resting in contact with the line selected through the agency of vertical and rotary magnets s^3 , s^4 ; if the line be busy then a circuit will exist from upper wiper s' to the tip of the plug and through the relay R' to ground in case the line tested has called or to another wiper s' and thence through a trunking equipment following the path through contact of R^{14} , contact of R^{13} , conductor 100 14 and winding of R^6 to ground if that line has been called; in either case the test relay R^{11} will be energized and in turn will 105 energize the release magnet s^6 . If, however, the selected line with which the test wiper rests in contact is not busy no circuit will exist from that test wiper to ground and the test relay R^{11} will not be energized; a branch path from the conductor 63 exists through the talking conductor of the trunk to the left hand contact of relay R^{14} and thence to an armature contact of relay R^{13} where it terminates open, but subsequent to the energization of relay, R^{14} as about to be described, this branch path passes to the inner contact of the left hand armature of that relay and thence over the conductor 41 to the right hand switch of the solenoid R^{15} which during the test period is open, and thus test 115 120 125 130

relay R^{11} has its circuit open at all points and the design of the device as a whole is that no energization of that relay may result when the line selected is in a condition 5 of disuse and subject to use in the connection now being established.

(2.) The relay R^{12} is energized over the path B, 42, 56, R^{12} , 57, 46, 47 and ground. By the closure of the left hand armature of 10 relay R^{12} , circuit is formed through elements B, 42, 56, armature of R^{12} , 60, winding of R^{13} , 61, switch s^5 and ground, energizing relay R^{13} which locks itself energized 15 over the circuit B, 42, 42, armature and inner contact of relay R^{13} , winding of relay R^{13} , 61, s^5 and ground. This energization of trunk-connecting relay R^{13} connects the conductors 13, 14 of the 20 trunk through to the outer contacts of the ringing relay R^{14} and through to the wipers s' . This furnishes a path through test relay R^{11} as follows:—B, 42, 24, 62, R^{14} , 63, talking conductor to left-hand armature of R^{14} , back contact and talking conductor to armature of energized relay R^{13} , conductor 14, winding of relay R^6 and ground; however, 25 this circuit is adapted to be opened by the attraction of the armatures of relay R^{14} , and it is the function of the connector switch that the opening of this circuit at R^{14} shall succeed its closing at R^{13} by a time limit so small that restoration of the connector switch is not permitted. It will be noted in the study of this time element that the 30 test relay R^{11} must attain the degree of magnetization required to attract its armature, must swing its armature through its full travel to close its contact, and that subsequently to the closure of the contact of R^{11} the release magnet s^6 must reach its required degree of magnetization and must overcome the inertia of its armature and move it through some definite arc before release of the switch S will be effected; this 35 series of necessarily consecutive operations limits the duration of the momentary false test here considered. The commutator X, as has been mentioned, is carried upon the shaft which carries the number wheels and 40 commutator devices Q¹, Q², Q³, Q⁴, etc., and the commutator X is adjusted angularly with respect to those wheels so that the conducting portion of X is in electrical connection with its brush at the time that the 45 energization of relay R^{13} occurs. It is seen therefore that by the closing of the contacts of relay R^{13} , by which current flow through test relay R^{11} was permitted, current flow also was simultaneously provided for 50 through path B, 42, X, winding of R^{14} , contact and armature r^{12} , 63, 50, r^{10} , 51 and ground. Thus current begins to flow through the winding of relay R^{14} at the same instant that current begins to flow 55 through the winding of relay R^{13} , etc., as-

suming equal speed in the operation of armatures, relay R^{14} will have moved its armature and will have broken its back contact, thereby cutting off current from relay R^{11} , in ample time to prevent the restoration 70 of the switch S by operation of release magnet s^6 , the break at the armature of R^{14} probably occurring in time to prevent any contact whatever at the armature of relay R^{11} . Thus a test condition is maintained 75 with the test wiper s' isolated from the winding of relay R^6 by the break at the armature of relay R^{14} , and the design and adjustment of the commutator X shall be such that the relay R^{14} is held energized 80 throughout the maximum period occupied by generator-selection impulses and until the opening of the circuit of the test relay R^{11} by the opening of the switch 62 upon release of the armature of the solenoid R^{15} . 85

The armature of the solenoid R^{15} is sluggish and does not open the switch 62 between the generator-selection impulses, so that the test circuit here described is maintained continuously during the period of 90 generator-selection.

Leaving the various parts of apparatus in the condition now considered, we will follow the action of the apparatus in response to the generator-selection impulses. In the instance assumed, since station No. 3 is to be called, three battery impulses will be received over the wire 14 operating the armature of the relay R^6 successively three times, which in turn acts over the path 47, 100 46, 57, R^{12} , etc. to operate the armatures of relay R^{12} in succession three times; the armature r^{12} through its front and back contacts effects the selection of the desired ringing generator as follows: Upon attraction of r^{12} 105 by the first generator-selection impulse, it makes electrical connection with its inner contact, but inasmuch as the wire 64 is open at the armature of relay R^{13} no complete circuit is closed. Upon the release of the 110 armature r^{12} at cessation of the first generator-selection impulse, circuit is closed through elements B, 42, 43, contact of R^{13} , 60, r^{12} , 65, contact of R^{16} , winding of R^{19} and ground, energizing relay R^{19} which locks 115 over the circuit B, 42, 43, contact of R^{13} , 60, 69, armature and contact of R^{19} , winding of R^{19} and ground. If but one generator-selection impulse were received, the generator G would remain in connection with conductor 120 40 ready for connection through conductor 41 to the ringing relay R^{14} . At the beginning of the second generator-selection impulse, relay R^{12} is energized and armature r^{12} is attracted, closing circuit through elements B, 42, 43, contacts of R^{13} , 60, r^{12} , 64, closed contact of lower armature of relay R^{19} , back contact of unenergized relay R^{20} , 125 winding of relay R^{16} and ground, energizing relay R^{16} which then locks over the circuit 130

B, 42, 43, contact of R¹³, 60, 69, armature contact and winding of R¹⁶. Upon the cessation of the second generator-selection impulse, the armature r¹² is released, closing circuit over B, 42, 43, contact of R¹³, 60, r¹², 65, closed contact of lower armature of energized relay R¹⁶, back contact of lower armature of unenergized relay R¹⁷, winding of relay R²⁰ and ground, energizing relay R²⁰ which then locks itself through its own contact by current received over conductor 69 to ground as in the case of relays R¹⁶ and R¹⁹. If no more generator-selection impulses were received, the effect of the two impulses thus far followed would be to leave generator G' connected to conductor 40 through contact of energized relay R¹⁶, that being the proper generator for ringing the second station on a party line. At the beginning of the third and last generator-selection impulse, the armature r¹² is again attracted, closing circuit over elements B, 42, 43, contact of R¹³, 60, r¹², 64, closed contact of energized relay R¹⁹, closed inner contact of energized relay R²⁰, closed outer contact of unenergized relay R²¹, winding of relay R¹⁷ and ground, energizing relay R¹⁷, which then locks itself by current through its own contact and winding over conductor 69 to ground. Upon the cessation of the third and last generator-selection impulse, the armature r¹² is released, closing circuit through elements B, 42, 43, contact of R¹³, 60, r¹², 65, closed inner contacts of energized relays R¹⁶ and R¹⁷, closed outer contact of unenergized relay R¹⁸, winding of relay R²¹ and ground, energizing relay R²¹ which then locks itself by current through its own armature contact and winding from conductor 69 to ground. This leaves relays R¹⁶ and R¹⁷ energized and leaves relay R¹⁸ unenergized, thus effecting the connection of generator G² to the conductor 40, and as the generator-selection impulses now cease, solenoid R¹⁵ releases its armature, opening the circuit of the test relay R¹¹ and closing the circuit between conductors 40—41, thus connecting the selected generator G² over conductor 41 to the inner contact of the left hand armature of ringing relay R¹⁴ and thus through the upper wiper s' and to the line conductor of the selected line to ring the third station upon the party line selected. The ringing will continue until the insulated portion of the commutator X passes under the brush of that commutator when the circuit of the winding of relay R¹⁴ will be interrupted and by release of that relay's armature the circuit from the wipers s' will be removed from the generator and carried to relays R⁷ and R⁶ respectively. The line selected will be subjected alternately to periods of ringing when the relay R¹⁴ is energized and to periods of non-ringing when the relay R¹⁴ is deenergized. Upon the

answering of the called sub-station, or of any sub-station upon that party line, during a period of non-ringing, current immediately will flow through elements B, 42, winding of R⁷, 13, lower s', line conductor, substation 70 bridge, return line conductor, upper s' 14, winding of R⁶ and earth, energizing R⁶ and attracting its armatures.

By the operation of the left hand armature of R⁶, circuit is closed through elements B, 42, left hand armature and inner contact of R⁶, winding of R¹⁰, 54, contact and left hand armature of R⁷, 55 and ground, energizing R¹⁰ which then locks over the circuit B, 42, right hand armature and contact of R¹⁰ to winding of R¹⁰, 54, contact and armature of R⁷, 55 and ground. By energization of relay R¹⁰, ground is taken off of wire 50 so that ringing relay R¹⁴ may not again be energized. Also by the energization and locking of R¹⁰ the relay R⁹ is released and remains released throughout the remainder of the connection. This is the condition of conversation and continues until the hanging up of the telephone 90 and the breaking of the substation bridge upon the called line.

Upon the hanging up of the telephone and the breaking of the substation bridge upon the called line, disconnection of the switch S is effected as follows: Circuit is interrupted over the return wire of the line and through relay R⁹ to ground, releasing the armatures of relay R⁶, but current continues through elements B, 42, winding of R⁷, 13, lower wiper s', and the sleeve side of the connected line and the winding of its cut-off relay N to ground, maintaining the energization of the relay R⁷. By the release of the left hand armature of relay R⁹ a release relay circuit is established through elements B, 42, left hand armature and outer contact of deenergized relay R⁶, winding of release relay R²², inner contact and armature r¹⁰, of relay R¹⁰, 51 and ground, energizing release relay R²² which, by closing its contact, energizes release magnets s⁶, which effects immediate restoration of all parts of the switch S to the normal position of disuse.

A consideration of test conditions during the process of the connection is desirable. When the test wiper or upper wiper s' connects with the test conductor of the line, no action is taken either to test for busy or to place a busy test upon the line until the wheels Q', Q², Q³, etc., have in due course of progress begun to send the generator-selection impulses; at this time, by the action of the solenoid R¹⁵, the selected line is tested for busy condition, the testing for busy being continued throughout the receipt of the generator-selection impulses and the line being left unguarded against connection by other connectors; at the close of the

generator-selection impulses, the test relay is taken off and the ringing generator is substituted. From this time a busy test guard condition is placed upon the test conductor of the selected line, being alternately the potential of the selected ringing generator when the relay R^{14} is energized, which is sufficient to energize any relay R^{11} which may test the line during the interval 5 of ringing, and between the intervals of ringing the busy test consists of the ground circuit through the relay R^6 . If the line thus connected with be tested for busy by some other connector attempting a connection 10 with it and during the interval of deenergization of ringing relay R^{14} , a current will flow from the connector then testing to the test conductor of the line, thence through the test wiper of the connector of Fig. 2 15 holding the line, and through back contact of relay R^{14} , front contact of R^{13} , 23, and winding of R^6 to ground. This current will be of sufficient strength to energize the test relay R^{11} of the distant connector attempting 20 to take the line being held, and this will effect disconnection of that connector but it will not be of sufficient strength to energize the relay R^6 inasmuch as by the energization and subsequent deenergization of that relay, the said testing current would also restore the holding connector of Fig. 2 to its 25 normal condition of idleness.

I have thus described and stated the operation of one form of my invention. Many 30 changes can be made therein without departing from the spirit thereof.

The equipment shown in the figures of the drawings herewith is sufficient as regards the automatic switching for an exchange 35 of 100 lines or less, in which there are say ten of the switches shown in Fig. 2, each line having ten multiple contacts s^2 . The invention is obviously applicable to exchanges of any size, however, by merely extending the circuits and increasing the operators in accordance with well understood rules. The particular form of switch employed is not material to the present invention, nor are the switch circuits shown in 40 Fig. 2 specifically necessary. They may be the same as those commonly employed in the Strowger system, using the switches shown in the Keith and Erickson patents hereinbefore referred to. The number of subscribers 45 may be anything desired, and the switching apparatus shown in Fig. 2 will be symmetrically increased proportionally thereto. The trunk lines 14-15 of Fig. 1, for an exchange of more than 100 lines 50 would pass to a first selector switch, which would be controlled in the same manner as the switch illustrated in Fig. 2, by impulses over the trunk wires, to pick out an auxiliary switch which would then be controlled 55 to take the next step and so finally to select

the line wanted. As this system of switching is familiar to those skilled in the art, and is shown in Letters Patent, it is unnecessary for me to go further into it here. The plugs P in front of an operator do not 60 represent any particular group of subscribers but are merely terminals of first selector or connector switches by which any subscriber in the exchange can be reached. An exchange of 100 lines with connector 65 switches only is shown, but as I have stated, this might as well be 1,000 or 100,000. In case of numbers having more than two digits, however, the number of sets of buttons in the sending device of Fig. 3 would of 70 course have to be increased accordingly, one row of buttons and one additional set of contact springs on the sending device being added for each digit. Thus, for a 1,000 line exchange there would be four rows of 75 buttons instead of three, in a 10,000 line exchange five rows and so on; one of the rows in each case being reserved for selective ringing as described herein.

My claims should be construed in view of the foregoing remarks as they are not intended to be limited to any particular number or arrangement of automatic switches or any particular number of subscribers' lines in an exchange. The gist of the invention lies in the combination and arrangement of the line terminals, the trunk plugs, the switches for completing the connections and the operator's sending circuits.

Having thus described my invention, what I claim and desire to secure by Letters Patent is:

1. In a telephone system, the combination of subscribers' lines, an answering jack and a calling signal for each of said lines, automatic connector switches in which multiples of said lines appear, trunks from switching plugs to said automatic switches the plug ends of said trunks being adapted to connect with said answering jacks, and a constantly-driven signal-sending device with locking signal-selecting keys for controlling the movements of said automatic switch to connect its trunk to the terminals of a desired line.

2. In a telephone system, the combination of subscribers' lines, a calling signal and answering jack for each of said lines, automatic connector switches in which multiples of said lines appear, trunks from answering plugs to said automatic switches, and a constantly-driven signal-sending device with a set of locking signal-selecting keys associated with each of said trunks for controlling the movements of said automatic switch to connect its trunk to the terminals of a desired line.

3. In a telephone system, the combination of subscribers' lines, a jack and signal for each of said lines, automatic connector

- switches in which multiples of said lines appear, trunks to said automatic switches, a switch plug for each trunk for connecting the trunk to a calling line, and a constantly driven signal-sending device with a bank of locking signal-selecting keys per trunk for controlling the movements of said automatic switch throughout a plurality of successive directory digits to connect its trunk to the terminals of a desired line.
4. In a telephone system, the combination of subscribers' lines, a calling jack and signal for each of said lines, automatic connector switches in which multiples of said lines appear, trunks to said automatic switches, manual means for connecting a calling line to one of said automatic switches, and a constantly driven signal-sending device with a bank of locking signal-selecting keys, associated with each of said trunks for controlling the movements of the automatic switch of the trunk throughout a plurality of successive directory digits to connect the trunk with a desired line.
5. In a telephone system, the combination of subscribers' lines, a jack and signal for each of said lines, automatic connector switches in which multiples of said lines appear, trunks to said automatic switches, plug ends on said trunks to connect with said answering jacks, and a constantly driven signal-sending device with locking selecting number keys, for controlling the movements of said automatic switch to connect its trunk to the terminals of a desired line.
6. In a telephone system, the combination of subscribers' lines, a jack and signal for each of said lines, automatic connector switches in which multiples of said lines appear, trunks to said automatic switches, plug ends on said trunks to connect with said answering jacks, and a constantly driven multiple-signal-sending device with locking selecting number keys and associated with said trunks for controlling the movements of said automatic switches to connect the trunks to the terminals of desired lines.
7. In a telephone system, the combination of subscribers' lines, a jack and signal for each of said lines, automatic connector switches in which multiples of said lines appear, trunks to said automatic switches directly from answering plugs, and a constantly driven multiple-signal-sending device for controlling the movements of an automatic switch to connect its trunk to the terminals of a desired line.
8. In a telephone system, the combination of subscribers' lines, a jack and signal for each of said lines, automatic connector switches in which multiples of said lines appear, trunks to said automatic switches directly from answering plugs, and a constantly driven multiple-signal-sending device for controlling the movements of an automatic switch throughout a plurality of successive directory digits to connect its trunk to the terminals of a desired line.
9. In a telephone system, the combination of subscribers' lines, a jack and signal for each of said lines, automatic connector switches in which multiples of said lines appear, trunks to said automatic switches, single-plug manual switching means for connecting a trunk and a calling line, a constantly driven signal-sending device, and locking signal-selecting keys associated with said trunks for controlling the movements of an automatic switch to connect its trunk to a desired line.
10. In a telephone system, the combination of subscribers' lines, a jack and signal for each of said lines, automatic connector switches in which multiples of said lines appear, trunks to said automatic switches, manual switching means for connecting a calling line with a trunk to one of said automatic switches, a constantly driven signal-sending device, and locking signal-selecting keys associated with said trunks for controlling the movements of an automatic switch to connect its trunk to the terminals of a desired line.
11. In a telephone system, the combination of subscribers' lines, a jack and signal for each of said lines, automatic connector switches in which multiples of said lines appear, trunks to said automatic switches, manual means for connecting a calling line with a trunk to one of said automatic switches, a constantly driven signal-sending device, and locking signal-selecting keys associated with each of said trunks for controlling the movements of its automatic switch through a plurality of successive directory digits to connect that trunk to the terminals of a desired line.
12. In a telephone system, the combination of subscribers' lines, a jack and signal for each of said lines, automatic connector switches in which multiples of said lines appear, trunks to said automatic switches, a constantly-driven multiple-signal-sending device, manual means for connecting a calling line to a trunk to an automatic switch, and sets of locking signal-selecting keys for each of said trunks whereby its automatic switch may be controlled to connect that trunk to the terminals of a desired line.
13. In a telephone system, the combination of subscribers' lines, a jack and signal for each of said lines, automatic connector switches in which multiples of said lines appear, trunks to said automatic switches, a constantly driven multiple-signal-sending device, answering plugs for connecting a trunk to a calling line, and sets of signal-selecting keys for each of said trunks whereby the automatic switch of that trunk may be controlled throughout a plurality of successive directory digits to connect its trunk to the terminals of a desired line.

- directory digits to connect that trunk to the terminals of a desired line.
14. In a telephone exchange system, a plurality of subscriber's lines, a plurality of 5 automatic switches and a trunk for each, single-plug switching means manually controlled by the operator for connecting an idle switch trunk to a calling line, automatic actuating means for the switches adapted to be manually preset so as to transmit the 10 whole number of the line wanted, and unitary means for each trunk manually controlled by the operator for determining the application of said actuating means to said 15 trunk, after setting up the number.
15. In a telephone exchange system, a plurality of line circuits each having a telephone and signal device at a substation, and a terminal answering jack with an associated 20 call signal at the central office, a number of connective circuits each comprising an answering plug adapted to coöperate with said jack, automatic switching apparatus for selecting and connecting with a wanted line, and a trunk directly connected to and terminating in said plug at one end and similarly connected to the switch at the 25 other, and controlling means for said switch-
- ing apparatus adapted to be manually actuated by an operator, and in turn to actuate 30 the switching apparatus, together with a common battery source of energy supplying all of said elements including the talking circuit.
16. In a telephone exchange system, a subscriber's line circuit terminating at a central office in an answering jack, an answering plug for said jack, an automatic switching apparatus adapted to connect with various subscribers' lines, a connective trunk directly 35 connected at one end to and terminating in said answering plug, and at the other end similarly connected to and terminating in said automatic switching apparatus, and means manually controlled at the central 40 office for actuating said switching apparatus, together with supervisory signal apparatus for the connector switch at the plug end of said trunk.
- In testimony whereof I affix my signature 45 in presence of two witnesses.

EDWARD E. CLEMENT.
